UNITED STATES PATENT OFFICE.

ERNST W. BUCKAU, OF NEW YORK, N. Y.

GOLF-BALL MOLD.

1,041,958.

Specification of Letters Patent. Patented Oct. 22, 1912.

Application filed September 29, 1911. Serial No. 651,988.

To all whom it may concern:

Be it known that I, ERNST W. BUCKAU, a citizen of the United States, residing at New York, in the county of New York and State of New York, have invented certain new and useful Improvements in Golf-Ball Molds, of which the following is a specification.

This invention relates to improvements in golf ball dies, cups or molds, the object thereof being to provide an improved golf ball mold which can be readily and inexpensively constructed and by means of which a perfectly round or spherical golf ball can be obtained having any desired shape of brambles thereon.

It is well known in practice that golf balls provided with brambles are not always perfectly round, due to the manner in which the same are molded. In other words, it has been the usual practice to provide the golf ball cup with projections to form recesses or brambles in the ball. It is extremely difficult, and frequently impossible, to get these projections all of the same depth, aside from the fact that the portions of the metal of the mold between the projections have to be chiseled or scraped out, which has to be done by hand, so that, aside from the fact that this is an expensive and difficult operation, it is almost impossible to get the projections all of the same depth, and consequently the ball is not usually a perfectly round ball.

The object, therefore, of the present improvement is to provide a golf ball cup or mold by means of which an absolutely true, round ball can be obtained, for the reason that all of the bramble forming recesses in the ball will necessarily be of the same depth.

In the drawings accompanying and forming part of this specification, Figure 1 illustrates a pair of the golf ball cups or molds in juxtaposition as they are usually placed when the ball is to be molded; Fig. 2 is a cross-sectional view of one of the molds; Fig. 3 is an enlarged detail view of a portion of the mold; Figs. 4 and 5 illustrate different forms of bramble forming devices; and Fig. 6 is a view of a portion of the molded ball.

Similar characters of reference indicate corresponding parts throughout the figures of the drawings.

In carrying out the present improvement,

each cup or mold 2 is scraped to a gage so as to form a perfect half sphere, this being of the same size as the ball to be molded. The semi-spherical wall of each mold is then drilled to form a series of openings 3 around the same for the insertion of the insert pieces or bramble forming members. These insert pieces which may be of any desired shape or form according to the kind of recesses to be molded into the ball, comprise a head 4 and a stem or projection 5, which is made about .0005 of an inch larger than the openings 3 in the mold. The mold or cup is then heated and the stems of the insert pieces are inserted into the openings or holes 3 and the mold allowed to shrink, whereupon the inserts will be held firmly in position. The mold is then properly washed with solder, which not only assists in holding the inserts in position, but keeps the cup from rusting. Since the cup is scraped, it follows that as the heads of the inserts are all of the same thickness a perfectly round ball can be obtained.

From the foregoing it will be observed that the bramble forming devices are formed separately from the mold, so that the mold can not only be scraped to gage, but a perfectly round ball can be obtained.

I claim as my invention:

1. A golf ball mold comprising a cup having a series of openings located over approximately the entire surface thereof and a series of bramble forming members having stems projecting into said openings.

2. A golf ball mold comprising a cup having a series of openings therein and bramble forming members having stems projecting into said openings and held therein by the shrinkage of the mold by permitting the same to cool after heating.

3. A golf ball mold comprising a cup-shaped member having a series of openings therein, and a series of bramble forming members having heads and stems larger than the openings in the cup and secured in such openings by first heating the mold and then inserting such stems and allowing the mold to cool.

4. A golf ball mold comprising a cup-shaped member having drilled holes therein and bramble forming members having stems projecting into said holes and retained therein by the shrinkage of the mold on the cooling thereof after heating.

5. A golf ball mold comprising two semi-

spherical cups, each having a series of openings therein, and a series of bramble forming members comprising heads larger than said openings and having stems rigidly secured in said openings.

6. A golf ball mold comprising two semi-spherical cups, each having a series of openings therein, and bramble forming members comprising heads having stems rigidly secured in said openings by heating and cool-

ing the cup and inserting the stems intermediate such heating and cooling operations.

Signed at 1821 Park Row Building, New York, N. Y., this 25th day of September, 1911.

ERNST W. BUCKAU.
